US0D1074565S

(12) **United States Design Patent** (10) **Patent No.:** **US D1,074,565 S**
(45) **Date of Patent:** **** May 13, 2025**

(54) **REMOTE CONTROL FOR A MARINE VESSEL**

(71) Applicant: **Brunswick Corporation**, Mettawa, IL (US)

(72) Inventors: **Ryan C. Abellera**, Fond du Lac, WI (US); **Todd D. Dannenberg**, Fond du Lac, WI (US)

(73) Assignee: **Brunswick Corporation**, Mettawa, IL (US)

(**) Term: **15 Years**

(21) Appl. No.: **29/990,734**

(22) Filed: **Feb. 24, 2025**

Related U.S. Application Data

(60) Continuation of application No. 29/897,967, filed on Jul. 21, 2023, now Pat. No. Des. 1,068,620, which is a continuation of application No. 29/832,427, filed on Mar. 28, 2022, now Pat. No. Des. 997,072, which is a division of application No. 29/757,010, filed on Nov. 2, 2020, now Pat. No. Des. 951,168.

(57) **CLAIM**

The ornamental design for a remote control for a marine vessel as shown and described.

DESCRIPTION

FIG. 1 is a rear perspective view of a remote control for a marine vessel according to our new and ornamental design; FIG. 2 is a side view thereof;

FIG. 3 is an opposite side view thereof;

FIG. 4 is a front view thereof;

FIG. 5 is a rear view thereof;

FIG. 6 is a top view thereof; and,

FIG. 7 is a bottom view thereof.

The broken lines illustrate the aspects of the remote control for a marine vessel that are not part of the claimed design.

1 Claim, 7 Drawing Sheets
